Patented April 28 1863

Ans. 1749

Henry C. Berlin of Bloomfield, N. J. & Geo. H. Jones of New York, N.Y.
Letters Patent No. 1749 Dated April 28, 1863.

The Schedule referred to in these Letters Patent is making part of the same.

To all whom it may concern:

Be it known that Henry C. Berlin, of Bloomfield,
County of Essex, State of New Jersey and Geo. H. Jones, of the City, County and State of New York, doing business under the name and firm of Berlin & Jones, in the City of New York, County and State of New York, have designed and produced a new style or pattern of an Envelope for enclosing Wedding Cards, and for a general enclosure for Notes or Epistolary correspondence: and we do hereby declare that the following is a full and exact description of the same, reference being had to the accompanying drawing.

The nature of our design is that the Envelope is Diamond form - as seen in the Drawing, Fig. 1 and 2;
instead of the square as heretofore used.

The whole forming altogether a new shaped Envelope being an oblong Diamond instead of oblong square form.
Also the upper Tab or flap of the Envelope as described in Fig
II (No 3) with three curves instead of the concentric as heretofore used.

That we claim . . . . as new and desire to secure by letter Patent is the new design for Envelope as shown and described.
